ABRASIVE WHEEL

Edward Van der Pyl, Holden, Mass., assignor to
 Norton Company, Worcester, Mass., a corpora-
 tion of Massachusetts

Application August 7, 1935, Serial No. 35,153

6 Claims. (Cl. 51-206)

The invention relates to grinding wheels and with regard to its more specific features to grinding wheels the central portion of which constitutes a non-abrasive metal disk.

5 One object of the invention is to provide a practical construction for grinding wheels of the type indicated. Another object of the invention is to provide a method of uniting an annular band of abrasive material to a disk center 10 which is economical in practice and which results in a strong and true wheel. Another object of the invention is to provide a unitary disk wheel construction of slight thickness and adequate strength. Other objects will be in part obvious 15 or in part pointed out hereinafter.

The invention accordingly consists in the features of construction, combinations of elements, arrangements of parts, and in the several steps and relation and order of each of said steps to 20 one or more of the others thereof, all as will be illustratively described herein, and the scope of the application of which will be indicated in the following claims.

In the accompanying drawing in which is 25 shown one of various possible embodiments of the mechanical features of this invention,

Fig. 1 is a sectional view of a portion of a disk to which is to be united a grinding annulus,

Fig. 2 is a sectional view of the structure shown 30 in Fig. 1, with the split peripheral part of the disk expanded and a grinding annulus in position to be secured to the disk,

Fig. 3 is a sectional view of the structure of 35 Fig. 2 after the split peripheral portion is closed upon the annulus,

Fig. 4 is a sectional view of a grinding wheel constructed according to the invention,

Fig. 5 is a plan or elevation of the wheel of 40 Fig. 4,

Fig. 6 is a fragmentary sectional view similar to Fig. 3, illustrating a modification of the invention.

Referring first to Fig. 1, I provide a disk 10 of thin metal stock which may have, as shown in 45 Figs. 4 and 5, a central hole 11 for mounting the completed wheel upon an arbor or central support of any suitable or desired type. For the disk 10 I preferably use soft steel but I may also use non-ferrous metals such as aluminum, copper, brass or any other metal or alloy. In any suitable manner, such as by means of a knife or wedge or any cutting instrumentality, I form a groove 12 in the periphery of the disk 10. This groove 12, as shown in Fig. 1, leaves a pair of 50 peripheral portions 13, 13 parallel and spaced

apart. In order to form the groove 12 I may mount the disk 10 upon an arbor, rotate it, and cut the groove with a very thin circular saw, guiding the edge of the disk 10 between rollers for accuracy. Or, on the other hand, I may use a 5 thin grinding wheel to form the groove 12. Grinding wheels of any thickness desired from .006" upwards already exist and for the grinding of soft metals such as those indicated are highly efficient. On the other hand, the groove 10 12 may be formed by splitting the metal as with a steel knife blade or the like while the disk 10 is being rotated, if desired.

Having thus formed the peripheral portions 13, I separate them as shown in Fig. 2, or I may 15 bend them backwards until they stand at right angles to the plane of the disk 10. This may involve some puckering of the material on account of the fact that the circumference is less as the diameter decreases, but this need not interfere 20 with carrying out the method as will appear. I then introduce the disk 10 inside of an annulus 15 comprising abrasive grit bonded with any suitable or known bond. Examples of abrasive grit 25 are aluminum oxide, silicon carbide, silicon dioxide, boron carbide and diamond. Examples of suitable bonds are shellac bonds, rubber bonds, natural and artificial resinous bonds, ceramic bonds, metallic bonds and the like.

Referring now to Fig. 3, I close the peripheral 30 portions 13 over the inside margin of the annulus 15. This may be done by mounting the disk 10 on the same or a different arbor, introducing rollers above and below the junction of disk and annulus and causing the rollers to approach while 35 rotating. Ultimately enough pressure should be exerted firmly to unite the parts mechanically. The rollers may be of large diameter and have grooves formed to correspond with the shape of the parts shown in Fig. 3 and considerable pressure 40 may be used in this rolling operation especially if the parts be carefully aligned and if an abrasive annulus of somewhat elastic properties be used. The invention lends itself particularly to the construction of a wheel including 45 an abrasive annulus bonded with a rubber or resinous bond which is not too brittle, since thin wheels are particularly useful for cutting-off operations, for sawing and the like and for such purposes a resilient bond which will not break 50 readily under stresses is preferred. Instead of rolling the peripheral portions 13, 13 onto the abrasive annulus 15, I may employ a swaging operation or the like.

Fig. 6 illustrates a modification of the invention. 55

tion in which the abrasive annulus 16 has a reduced portion 17 and the disk 18 has a thickness slightly less than the thickness of the grinding portion of the annulus 16. This results in a wheel particularly suited for deep cutting operations where the metal center 18 passes into the cut owing to the depth thereof, because the cut made by the abrasive portion 16 will be wider than the metal center at any point. Preferably the periphery of the annulus 16 is slightly wider than the combined width of the portions 19, 19 and the portion 17.

The construction of the invention lends itself particularly to the construction of wheels the grinding portion of which comprises diamond grit or abrasive bonded with any suitable or desired bond, such as artificial resinous material, for example. By the present construction, the grinding annulus including diamonds may be readily united to a metal center thus concentrating the diamond abrasive grit at the place of most efficiency. Furthermore, by the use of a metal center a wheel which has a very large diameter relative to its thickness may be constructed without impairing its strength. The disk 10 is not brittle and thus breakage of wheels is much reduced.

It will thus be seen that there has been provided by this invention a method and article in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

I claim:—

1. The method of making a composite wheel which comprises providing a thin metal disk, forming a groove in the periphery of the disk, providing an annulus of abrasive substance bonded with a suitable bond the inside diameter of

which is slightly greater than the diameter of the disk less twice the depth of the groove, opening the metal on either side of the groove, placing the disk in the annulus, and rolling or swaging the metal in place.

2. A grinding wheel comprising a metal center, an annulus of abrasive material extending outwardly from said metal, and a junction of metal center and annulus comprising split peripheral portions of the center surrounding and gripping the inner marginal sides of the annulus, the metal center and the said peripheral portions constituting an integral piece.

3. An abrasive wheel comprising a soft metal disk, an annulus of abrasive material there being a reduced portion at the inside thereof extending circumferentially, there being a cut or groove in the periphery of the disk, peripheral portions formed by the cut or groove lying on either side of the reduced portion and being pressed into union with the annulus, the said peripheral portions and the soft metal disk constituting an integral single piece.

4. An abrasive wheel as claimed in claim 3 in which the outer part of the abrasive annulus is thicker than the remainder of the wheel.

5. A grinding wheel comprising a soft, thin metal disk having a central hole, said disk having its side faces in parallel planes, an annulus of bonded abrasive material of a thickness substantially that of the disk and having its side faces in parallel planes and the radial dimension of said annulus being substantial as compared to the thickness thereof, and a groove extending peripherally around the disk and separating the metal of the disk at the periphery into peripheral portions which lie in parallel relation in engagement with the annulus, holding the annulus to the disk.

6. An abrasive wheel as claimed in claim 5 in which the inner part of the annulus is reduced in thickness so that the outside surfaces of the peripheral portions are flush with the outer surfaces of the disk and of the abrasive annulus.
